[57] CLAIM

The ornamental design for a top and sides of a front cover for a printer, as shown and described.

DESCRIPTION

FIG. 1 is a right side perspective view of a top and sides of a front cover for a printer showing our new design, the broken lines are for a printer being for illustrative purposes only and form no part of the claimed design;

FIG. 2 is a front view thereof;

FIG. 3 is a top view thereof;

FIG. 4 is a right side view thereof;

FIG. 5 is a left side view thereof; and,

FIG. 6 is an enlarged view of the operator panel as seen in FIG. 3.

The bottom of the embodiment is not being claimed.
